UNITED STATES PATENT OFFICE.

ALONZO A. WARNER, OF NEW BRITAIN, CONNECTICUT, ASSIGNOR TO LANDERS, FRARY & CLARK, OF NEW BRITAIN, CONNECTICUT, A CORPORATION OF CONNECTICUT.

ELECTRIC TOASTER.

1,080,667.

Specification of Letters Patent.

Patented Dec. 9, 1913.

Application filed May 20, 1912. Serial No. 698,386.

To all whom it may concern:

Be it known that I, ALONZO A. WARNER, a citizen of the United States, and a resident of New Britain, in the county of Hartford and State of Connecticut, have invented certain new and useful Improvements in Electric Toasters, of which the following is a specification.

The object of this invention is to produce an electric toaster for bread, etc., having features of novelty and advantage.

In the drawings Figure 1 is a side elevation of a toaster embodying my invention. Fig. 2 is an end view with parts being broken away to show construction. Fig. 3 is a sectional plan view of a portion of the device taken on the line *a* of Fig. 1. Fig. 4 is a sectional side view of the parts shown in Fig. 3.

20 Referring to the drawings *a* denotes the base which is preferably made of sheet metal provided at its ends with feet in the form of disks 2 located between the out-turned ears 3 and secured by the pins 4.

25 The disks may be notched as at 5 so as to project slightly above and engage the edge of the base. This is an inexpensive and extremely satisfactory structure for finishing the base and providing suitable foot pieces. If desired, these disks can be made of insulating material.

30 On the base is secured a standard 10 formed from sheet metal and which constitutes the support for the toaster proper. At 35 either end of the standard a lip 11 is turned up. The frame 15 of the toaster is of inverted U shape with its side arms lying against these upturned lips 11. Fitted against the inner faces of the side arms of 40 the frame are plates 16, 16 secured at the top as by the screws 17, 17, slotted along the median line as indicated at 18, and preferably corrugated at this point as clearly seen in Figs. 3 and 4. The ends of the frame 45 arms and the lower ends of these plates are secured to the lips 11 by the clamps 12 and screws 13, binding the structure together and securely supporting it on the standard.

The heat is produced by passing an electric current through suitable resistances which constitute a heating unit. This heating unit I prefer to make in three sections 20, 30, 40. The resistance as illustrated is in the form of a wire coiled about a core of insulating 55 material. The cores which are the same in

each section of the unit can conveniently be made of layers of mica 22 stiffened by a strip of metal 23 passing centrally through them between the layers. The ends of these cores are seated in the grooves 18 in the 60 plates 16, and by corrugating the plates in the grooved part, a deeper bearing for the ends of the cores is secured as clearly seen in Figs. 3 and 4.

The sections of the units are arranged one 65 above the other spaced apart slightly and connected together by the links 34. The resistance wire 25 is wound more closely on the lower section 20 than is the resistance wire 35 on the intermediate section 30, which 70 in turn is more closely wound than the resistance wire 45 on the upper section 40. This may be one continuous wire starting at one terminal 50 and wound successively upon the separate sections, and then brought back 75 to the other terminal 51, or they may be separate wires joined together in some convenient way. This is not material so far as certain features of the invention are concerned.

80 Guard wires 55 pass through apertures in the top of the frame, and their ends enter apertures in the standard. This keeps the bread, or other material, from lying directly against the unit and so prevents burning. 85 Holders 56, 56 are pivoted on cross bars 57 near the bottom of the toaster and are pressed by the springs 58 against the frame with the result that they hold the bread closely against the guard wires. These 90 holders can conveniently be made by bending up a wire to shape, as clearly illustrated, providing it with the inturned projections 59 to receive a cross bar 60 made of sheet metal with portions folded over at each end to 95 keep the material evenly pressed against the guard wires. A base 61 attached to the sides of the holder forms a bottom support for the material which is being toasted. A top 70 is provided with depending spring 100 arms 71 channeled at their ends to slide on the frame, and apertured to receive the heads of the screws 17 which constitute holding and positioning devices. This top prevents the too rapid escape of heat, and can conveniently be used for keeping toast and other materials warm.

105 While I have described the illustrated embodiment in detail, nevertheless I do not wish to be understood as limiting myself to 110

the exact construction shown and described, but on the contrary, desire to claim protection for any modifications which may come within the spirit of the invention.

5. I claim as my invention:—

1. In a device of the character described, a base, a frame supported thereon, a sectional heating unit mounted in the frame, the sections of said unit being of similar 10 shape and arranged closely together edge to edge in the same plane, with the adjacent edges of said sections approximately parallel, and means for electrically heating the lower part of said unit to a greater extent 15 than the upper part thereof.

2. In a device of the character described, a base, a frame mounted thereon, a sectional heating unit supported in said frame, the sections being arranged one above the 20 other in the same plane with their adjacent edges arranged closely together and approximately parallel to one another, said sections comprising cores of insulating material with a resistance wire wound thereon, 25 the number of turns of said resistance material on the lower section being in excess of the number of turns of the resistance material on the upper section.

3. In a device of the character described, 30 a base, a frame supported thereby, the sides of said frame being longitudinally corrugated and slotted in the top of the corrugation, and a heating unit comprising a thin wide core whose ends are adapted to fit 35 within the slots, and a resistance material mounted on said core.

4. In a device of the character described, 40 a base, a frame of inverted U-shape having its side arms secured to the base at their 45 ends, longitudinally corrugated and slotted plates secured to the inner faces of said side arms, and a sectional heating unit supported in said frame, said sections being arranged one above the other, and each section comprising a thin wide core whose ends are 50 adapted to fit in the slots and resistance material mounted on the core.

5. In a device of the character described, a base, a frame of inverted U-shape having its side arms secured to the base at their 55 ends, longitudinally corrugated and slotted plates secured to the inner faces of said side arms, and a sectional heating unit supported in said frame, said sections being arranged one above the other, and each section comprising a thin wide core whose ends are 60 adapted to fit in the slots and a resistance wire wound upon said cores, said wire being wound more closely upon the lower core than upon those above it.

6. In a device of the character described, a base, upturned lips at the ends thereof, a frame of inverted U-shape having the ends of the side arms located against said lips, means for clamping said arms to said lips, 65 and a heating unit supported by said frame.

7. In a device of the character described, a base, upturned lips at the ends thereof, a frame of inverted U-shape having the ends of its side arms located against said lips, 70 plates secured to the inner faces of the side arms, clamps to secure said plates and arms to said lips, and a heating unit supported in said plates.

ALONZO A. WARNER.
